GAS PERMEABILITY CHAMBER
Peter O. Karlowicz, 4911 Higbee St., Philadelphia, Pa.
Filed Nov. 30, 1960, Ser. No. 72,811
3 Claims. (Cl. 73—38)
(Granted under Title 35, U.S. Code (1952), sec. 266)

The invention described herein may be manufactured and used by or for the Government for governmental purposes without the payment to me of any royalty thereon.

This invention relates to an apparatus with which the permeability of specimens (frequently of metal and made by a powder metallurgy process) may be tested. It has for an object to provide such an apparatus in which the desired test may be made more quickly and easily than has been customary heretofore.

One cause of greater time consumption under the prior art has been the necessity for tightening and releasing a plurality of clamping screws for the assembly and removal of a test specimen. Another difficulty has been in obtaining the proper alignment of the test specimen between the clamping members when performed expeditiously. A further disadvantage in some of the prior apparatus has been the necessity for deforming the necessary gaskets in applying pressure to them by rotation of a contiguous part. Still another trouble in such apparatus has been inaccuracy and the inability to obtain reproducible results with the same specimen, due to a leakage of gas, caused by mentioned faults.

According to the present invention these disadvantages have been eliminated. A single screw applies the desired pressure equally to opposed clamping members for holding a test specimen between them. To reduce the danger of pressure being applied non-uniformly or elsewhere than intended these opposed clamping members holding the work have recessed portions in which legs applying pressure to the outside of each are accurately positioned. Four dowels in the upper plate fitting in four recesses in the lower plate prevent sliding or misalignment.

Referring to the drawing:

FIG. 1 is a side view showing a preferred embodiment of the present invention.

FIG. 2 is a view taken on the left side of FIG. 1.

Clamping members 10 and 11 have the test specimen 13 held between them in a cut-out portion 12 of one member to insure its being positioned where desired. Gaskets 14 and 15 have a central perforation through which gas is supplied or vented from the specimen 13. The recessed portions 29 in member 11 are not so deep as to preclude the application of the desired pressure to a specimen through gasket 14 and a larger gasket 16. Connections for gas are made at 17 and 18 in any convenient manner and passageways 19 and 20 lead through members 10 and 11 from connections 17 and 18 as has been customary. The cut-out portion 12, as depicted in the drawings, is centrally disposed within member 11 and will be of sufficient depth to accommodate gaskets 14 and 15 and the specimen 13 to be tested therebetween. The cut-out portion 12 will preferably be circular in shape for economy and ease of fabrication.

Instead of a plurality of screws, only one screw 21 is provided for applying pressure to and through each

2

clamping member and the test specimen. This screw may be actuated by a knurled head 22 or in any convenient manner and engages inside threads within a frame 23 having four leg portions (three being shown 24, 25, 26) leading to the underside and corners of member 11. Pressure from screw 21 is applied to pressure distributor 27, also having four leg portions and leading to the four corners of the upper member 10. Recessed portions 28 and 29 of clamping members 10 and 11 respectively assist in the proper positioning of the clamping leg portions contiguous each clamping member. As shown in FIG. 2 the clamping members 10 and 11 are of the same width as frame 23 and due to the pressure distributor 27 being aligned with screw 21 by the rounded end 30 of the screw 15 engaging a similarly rounded recess 31 to assist in centering the distributor with respect to the axis of screw 30 there is little if any need for centering the members 10 and 11 with respect to the frame 23 and distributor transversely of the frame as shown in FIG. 1. A greater need 20 exists for such centering transversely of FIG. 2, which is why recessed portions 28 and 29 are provided, each bounded by a guide flange as illustrated in FIG. 2. Four dowels 32 in upper plate fit in four recesses 33 in lower or bottom plate to insure perfect alignment and prevent 25 any sliding of plates.

I claim:

1. A gas permeability chamber for measuring the permeability of specimens and comprising an upper clamping member having recessed portions at its upper part 30 and a lower clamping member having recessed portions at its lower part, said lower clamping member having a cut-out portion at its upper part, a pair of gaskets sandwiching said specimen all disposed within said cut-out portion, a gas passageway in each of said clamping members and said gaskets so aligned to pass gas generally vertically centrally of said specimen, a frame threaded at its upper end and having upwardly extending legs at its lower end engaging said recessed portions of the lower clamping member, a pressure distributor within said frame and spaced therefrom, said distributor having a round recess at its uppermost portion and legs to engage the recessed portions of said upper clamping member, a screw 35 engaging said threads at the upper end of said frame for nesting within said round recess of said distributor for applying vertical pressure through the legs of said frame and distributor to insure an air-tight fit between said clamping members and means for passing gas through said passageway.

2. The device of claim 1 further characterized by 40 doweled connections in the clamping members.

3. The device of claim 2 further characterized by a third gasket mounted between the clamping members and having aligned holes therewith for receiving dowels and gas passageway.
